BREAST FORM AND BRASSIÈRE

Stella De Jorio, La Canada, Calif.

Application May 20, 1936, Serial No. 80,799

3 Claims. (Cl. 128—282)

This invention relates to the art of sanitary pads or dressings and has to do more particularly with a sanitary absorbent breast form, to be used in conjunction with an impervious brassière.

An object of the present invention is to supplement a subnormal female breast after a breast amputation with an inexpensive sterile absorbent breast form. This is accomplished by providing a bust form composed of alternate layers of sterilized materials, such as cotton and cellulose fibers covered with a gauze or cloth sheath, whereby discharges from the breast wound are conveyed to the body of the bust form by means of the capillary action of cellulose fibers.

Another object of the invention is to protect the clothes of a nursing mother from overflowing milk ducts in the breast, and at the same time allow such mother to easily gain access to the breast.

This is accomplished by providing a soft, non-irritating concave breast form, composed of sterilized cotton and cellulose fiber covered with a sheath of sterile gauze or the like, and a protective brassière made of a soft impervious material such as softex. A trough in the brassière is adapted to receive a supporting arm, integral with the pad, and thereby maintain such pad and its complementary breast in relative proximity to each other. An aperture is provided in the brassière adjacent each breast pad and is opened or closed by means of a standard slide fastener. In this way a wet pad may be removed with comparative ease.

Many other advantages will be apparent from the following detailed description when read in conjunction with the accompanying drawings, wherein:

Fig. 1 is a rear elevation of the brassière of this invention.

Fig. 2 is a front elevation showing the brassière and a complementary sanitary absorbent breast pad.

Fig. 3 is a side elevation showing a preferred form of concave absorbent breast pad.

Fig. 4 is a front elevation of the brassière of this invention in place on a female figure.

Fig. 5 is a back elevation of the brassière or harness of the invention showing the construction thereof.

Fig. 6 is a front elevation of a female figure with the absorbent breast form in place.

Fig. 7 is a side elevation partly in cross section of an absorbent breast form for use with an amputated breast.

Referring now to Fig. 1, the brassière 1 con-

sists of a harness 2 shaped to fit a female figure. A pair of supporting shoulder straps 3 and 3' are adjustably fastened by means of a conventional button and buttonhole arrangement 4, conveniently located adjacent the shoulder of a wearer. Adjustable belts 5 and 5' are continuations of the straps 3 and 3', and secure the base of the brassière firmly around the torso of the wearer. The brassière 2 is so constructed that the belts 5 and 5' are adapted to cross at the back of the wearer as shown in Fig. 5. Belt 5 passes through an aperture 40 at the side of the brassière 2 and is adjustably fastened at the front of the wearer in a conventional manner. Thus by adjusting the belts 5 and 5' an upward pressure is exerted upon breast pockets 36 and 37, thereby elevating the breasts of a wearer and assisting the breast muscles in holding the breasts in a proper position.

A trough or pocket 6 is located at the base of the harness 2 and the front of the harness 2 is arranged in the form of two breast pockets 36 and 37. Each pocket is adapted to receive a breast pad such as 7. An extended tongue 8 on the pad 7 is adapted to be received in the reservoir in the bottom of the trough 6, thus providing a firm support for pad 7 and preventing it from slipping out of place. This reservoir is formed by stitching, as indicated in Figure 3 and referred to by numeral 8', this separating the reservoir from the rest of the trough. A flap 9 covers an aperture 10 in the breast pocket 36 of the brassière or harness 2 and provides a body-guard for a conventional slide fastener 11, which serves to open and close aperture 10 at will. The same arrangement is used for each breast as is shown in Fig. 4, wherein the second slide fastener 12 is used to close aperture 38 (similar to aperture 10) in the breast pocket 37.

Different types of sanitary breast pads are designed to be used in conjunction with this brassière, varied in shape according to the breast condition that is to be corrected. Thus, where the device is being used by a nursing mother to protect her clothes from excess flow from her milk ducts, a pad such as 7, shown in Fig. 3, is used wherein the pad 7 consists of a series of alternate layers of cellulose fiber and absorbent cotton 14—15—16—17 pressed into a substantially concave cone shape to fit an enlarged breast. Pad 7 is covered with a notched gauze or cheese cloth sheath 18, stitched to pad 7 to form a tight fitting cover. The lower side 19 of pad 7 is thicker than the upper side 20 in order to absorb

excess milk flowing downward toward the trough 6, as will be readily understood.

In order to provide a greater amount of absorbent material where needed and also to afford a firm support for the pad, an extension or pendant arm 8 is attached to the main body of pad 7 and is adapted to rest upon the bottom of the trough 6 and prevent pad 7 from slipping when it is in position. It will be seen that if pad 7 and extension 8 become saturated any excess milk will be caught in the impervious trough 6, where it will not be able to soil the wearer's clothing.

In the case of a wearer suffering from a diseased condition of the breast and where there has been an amputation of the breast or breasts and discharges are likely to occur, a pad such as 22 Fig. 7 is used. This pad 22 is not only used to absorb discharges but also supplements a human figure such as 23, and preserves its contours as is shown in Fig. 6. Pad 22 consists of a series of layers of absorbent cotton 24—26—28—31 and 32, and alternate layers of cellulose fiber 25—27—29 and 30 compressed into the shape of a human breast.

It must be understood that the pads are made in various standard sizes to approximate the normal measurements of a wearer.

A sheet wadding covering 39 is used to cover pad 22 and serves as a framework upon which the alternate layers of absorbent material are stitched. A sterilized gauge covering 33 is suitably notched and sewn to form a tight sheath covering for the whole assembly.

A tape or bias binding 34 is fastened along base edge of pad 22 to lend it rigidity and help it retain its shape. A forward part 35 of pad 22 is gathered and stitched to give the semblance of a nipple.

Sheath 33 may be in white, brown, yellow or flesh colored cloth to suit the type of skin of the wearer.

It will be seen that pad 22 may be inserted and removed at will through apertures 10 and 38, and thus provide an easy method of keeping a sanitary dressing near a dangerous breast condition where sterile dressings are absolutely necessary.

It is to be understood that many different combinations of different sanitary materials may be used to form the pads without departing from the spirit of the invention.

Having thus described my invention, what is claimed as new and desired to secure by Letters Patent is:

1. In a garment, a breast receiving member and a trough, said trough adapted to be located below and in peripheral relation thereto, a pad comprising a plurality of alternate layers of absorbent and impervious material shaped to resemble an entire human breast, a reservoir distinctly formed in said trough below the periphery of said breast receiving member, an arm of absorbent material formed integral with said pad extending downwardly and adapted to be received in said reservoir, an aperture located in front and on each side of said garment, means for opening and closing said apertures, said means positioned in an arc over the center of the pad.

2. In a garment, a breast receiving member and a trough, said trough adapted to be located below and in peripheral relation thereto, a pad shaped to resemble an entire human breast, a reservoir distinctly formed adjacent said trough below the periphery of said breast receiving member, an arm extending downwardly from said pad and adapted to be received in said reservoir to receive the moisture from said pad.

3. In a garment of the class described having breast receiving members, U-shaped trough members secured to the outside of said garment in cooperative relationship with said breast receiving members, moisture absorbing members comprising a plurality of alternate layers of absorbent and impervious material shaped to snugly engage the human breasts and disposed within said trough, arms formed from said pads and extending below the periphery of said pads, smaller troughs formed by stitching in the lower central portion of said main troughs and adapted to receive said extended arms, cover members for said pads secured at the top to said garment and over said pads.

STELLA DE JORIO.
